INVENTOR
McKay Wright
BY
Fred C. Matheny
ATTORNEY

UNITED STATES PATENT OFFICE.

McKAY WRIGHT, OF SEATTLE, WASHINGTON.

RADIOANTENNA.

Application filed September 16, 1926. Serial No. 135,836.

My invention relates to improvements in radio antennæ for use in connection with radio receiving apparatus and the object of my invention is to provide a radio antenna 5 that may be suspended vertically from the side of a building or from any suitable support thus making it possible to dispense with the usual overhead antenna wires and the unsightly posts and supports for the same and saving a great deal of time, labor and expense in installation.

Another object is to provide an antenna that is extremely sensitive, highly selective and nondirectional.

15 A further object is to provide an antenna that has a condenser incorporated into its construction.

A still further object is to provide a radio antenna in the nature of a vertically arranged copper pipe.

20 A more specific object is to provide efficient bracket means for suspending said copper pipe and supporting the same against swinging movement.

25 Other and more specific objects will be apparent from the following description taken in connection with the accompanying drawings.

30 In the drawings Figure 1, is a view in side elevation of a radio antenna constructed in accordance with my invention as the same may appear when set up and ready for operation.

35 Fig. 2 is a longitudinal sectional view of an antenna pipe having a condenser provided in its lower end.

Referring to the drawings, throughout which like reference numerals designate like parts, 5 designates a bracket of strong and 40 substantial construction and ornamental appearance that is adapted to be secured as by screws 6 to a support 7, as to the side of a building and that is provided at its outer end with a hook 8, arranged to be connected by a link 9 with an insulator 10, which is rigidly secured within the top end of a pipe 11 of copper or like metal. The insulator 10 is preferably sealed within the top end of the pipe 11 so as to exclude all forms of moisture.

50 Another insulator 12 is rigidly secured to the pipe 11 toward the lower end and projects at right angles from said pipe. A rod 13 hereinafter termed a wind arm has one end secured by a bolt 14 to the bottom portion of the bracket 5 and is provided on the

other end with a hook portion 15 that is bent at right angles and is adapted to project into a suitable hole 16 in the end of the insulator 12. The bolt 14 extends through a curved portion of the bracket 5 and is connected with the end of the wind arm in such a manner as to produce a spring flexure in said wind arm and to cause said wind arm to exert a downward pressure on the insulator 12 thus always tending to exert a downward pull on the pipe 11 keeping said pipe under a slight tension and preventing rattling or noise between the insulators and the parts connected therewith. The wind arm 13 further prevents substantially all swinging movement of the pipe 11.

Concealed within the lower end of the pipe 11 is a condenser 17 having one terminal connected with the pipe through the cross rivet 18 and the other terminal connected with a binding post 20 that projects outwardly through a disc 21 of insulating material that is sealed within the bottom of the pipe. Another binding post 22 is connected directly with the side of the pipe. The lead in from the antenna to the receiving instrument will preferably be composed of two wires 23 and 24 one wire being connected to the terminal post 20 and the other 85 wire being connected to the binding post 22. One of these wires only will be connected with the instrument at any one time so that the instrument will either be connected directly with the antenna pipe 11 or 90 will be connected with said pipe through the condenser. The same results may be obtained by the use of a single lead in wire which may be selectively connected with either the binding post 20 or 22 this latter 95 method is less convenient and is therefore less desirable.

In practice I find that excellent results with this antenna are secured when I use a one and one-quarter inch antenna pipe two and one-half feet long and a certified condenser of .0001 microfarads capacity. This condenser may be of the mica and plate type.

After all of the parts in connection with the antenna tube 11 are assembled said tube 105 and assembled parts are thoroughly treated as with paraffine and shellac to render the tube absolutely moisture proof.

This antenna is non-directional due to the fact that it is formed of a cylinder of metal 110 suspended vertically. It is very sensitive in picking up electromagnetic waves from dis-

tant transmitting stations and does not need to be elevated to any great height but may be suspended from the wall of a building thereby making it possible to dispense with 5 unsightly overhead antennae that are difficult and dangerous to install and handle especially when they are in close proximity to power transmission lines and also greatly reducing the danger from lightning. It is 10 further at right angles to most of the eddy currents arising from transformers power wires and the like.

This antenna is highly selective when used 15 without the condenser 17, but the selectivity is considerably increased when the connection to the antenna pipe is made through said condenser.

I find that much better results are obtained 20 by the use of a copper pipe with walls of substantial thickness than are obtained by the use of a thin walled tube or a solid bar of copper.

The entire assembly is neat and symmetrical and is an ornament to a building when 25 installed thereon.

The foregoing description and accompanying 30 drawings clearly disclose a preferred embodiment of my invention but it will be understood that this disclosure is merely illustrative and that such changes in the device may be resorted to as are within the scope and spirit of the following claims.

I claim:

1. A radio receiving antenna embodying a 35 piece of insulated copper pipe having relatively heavy walls and supported in insulated relation in a vertical position, a condenser disposed within the lower end of said pipe means in said pipe above said condenser for supporting the condenser and electrically connecting one terminal of the same to said pipe, an insulator member forming a closure for the bottom end of said pipe and having a terminal post extending therethrough for

connecting the other terminal of said condenser with a receiving instrument and another binding post connected directly with the bottom end of said pipe. 45

2. In a radio receiving antenna, a right angled bracket arranged to be secured to an 50 upright support, a radio antenna pipe, an insulator in the upper end of said pipe arranged to be connected with said bracket to suspend said pipe vertically, another insulator secured to the lower end of said pipe 55 and extending at right angles therefrom and a wind arm connecting said last named insulator with the lower portion of said bracket.

3. In a radio receiving antenna, a right angled bracket, an antenna pipe suspended 60 from said bracket in insulated relation therefrom, a rigid insulator projecting at right angles from the lower end of said antenna pipe and a wind arm of resilient metal connected with said insulator and secured to the 65 lower end of said bracket and arranged to exert a downward force on said insulator and prevent swinging of said pipe.

4. In a radio receiving antenna, a right angled bracket arranged to be secured to a 70 vertical support and having a hook portion on its outer end, an antenna pipe having an insulator sealed in its upper end, means connecting said insulator with said hook for suspending said pipe, another insulator 75 rigidly secured to the lower end of said pipe and extending sidewise therefrom and having a transverse hole in its outer end, and a resilient wind arm rigidly secured to the lower end of said bracket and having a 80 downturned outer end arranged to engage within the hole in said insulator, said wind arm being adapted to exert a downward pressure on said insulator.

The foregoing specification signed at 85 Seattle, Washington, this 8th day of Sept. 1926.

McKAY WRIGHT.
